7 Claims

ABSTRACT OF THE DISCLOSURE

This invention relates to the discovery of a group of compounds herein described as 2-amino-4,5,6,7-tetrahydro-4,7-ethanethieno[2,3-b]pyridines which are effective topically against *Herpes simplex/H₄/virus*, *Herpes simplex/2/ALA/SM virus* and adenovirus-2.

SUMMARY OF THE INVENTION

This invention relates to compounds of the formula

where R₁ is

where

R₂ is hydrogen, alkyl of one through six carbon atoms; X is oxygen or sulfur;
R₃ is hydrogen or alkyl of one through four carbon atoms;
R₄ is hydrogen or alkyl of one through four carbon atoms and the pharmaceutically acceptable non-toxic salts of said compounds.

Another aspect of the invention is to demonstrate the inhibition of growth of *Herpes simplex/H₄/virus* and *Herpes simplex/2/ALA/SM virus* when at least 10 mcg./ml. are applied to a culture medium containing infected rabbit kidney cells or mouse embryo cells respectively.

In addition, the antiviral activity of the compounds of this invention can be further demonstrated against adenovirus-2 when an agar medium containing HEp-2-cell monolayers and 80 mcg. of the compound, 2-amino-4,5,6,7-tetrahydro-4,7-ethanethieno[2,3-b]pyridine - 3 - carbonitrile shows no damage to said HEp-2-cells after an incubation period of 7 days at 37° C. as compared to controls.

Still another aspect of the invention is to show that shaved guinea pigs infected intradermally with *Herpes simplex/H₄/virus* showed only 38% positive lesions after 7 days as compared to control animals which showed 86% positive lesions when a compound of the invention was administered topically.

DESCRIPTION OF THE INVENTION

As summarized above, this invention relates to compounds of the formula:

2

where R₁ is

5 where

R₂ is hydrogen or alkyl of one through six carbon atoms; X is oxygen or sulfur;
R₃ is hydrogen or alkyl of one through four carbon atoms;

10 R₄ is hydrogen or alkyl of one through four carbon atoms; and

the pharmaceutically acceptable non-toxic salts of said compounds.

15 2-amino-4,5,6,7-tetrahydro-4,7-ethanethieno[2,3-b]

pyridine-3-carbonitrile.

2-amino-4,5,6,7-tetrahydro-4,7-ethanethieno[2,3-b]

pyridine-3-carboxylic acid ethylester.

2-amino-4,5,6,7-tetrahydro-4,7-ethanethieno[2,3-b]

pyridine-3-carboxamide.

20 It will be understood that the term non-toxic pharmaceutically acceptable salts includes those salts of the compounds of this invention which are suitable for administration to warm-blooded animals. Representative of such salts are the hydrochlorides, hydrobromides, sulfate, phosphates, acetates, nitrates, succinates, adipates, propionates, tartrates, cyclohexylsulfamates, citrates, bicarbonates, and pamoates. Of these the hydrochloride salt is preferred.

Illustrative of the compounds of this invention are the 30 following:

2-amino-4,5,6,7-tetrahydro-4,7-ethanethieno[2,3-b]

pyridine-3-carbonitrile.

methyl 2-amino-4,5,6,7-tetrahydro-4,7-ethanethieno

[2,3-b]pyridine-3-carboxylate.

35 ethyl 2-amino-4,5,6,7-tetrahydro-4,7-ethanethieno

[2,3-b]pyridine-3-carboxylate.

isobutyl 2-amino-4,5,6,7-tetrahydro-4,7-ethanethieno

[2,3-b]pyridine-3-carboxylate.

2-amino-4,5,6,7-tetrahydro-4,7-ethanethieno[2,3-b]

pyridine-3-carboxylic acid.

2-amino-4,5,6,7-tetrahydro-4,7-ethanethieno[2,3-b]

pyridine-3-carboxamide.

N-methyl-2-amino-4,5,6,7-tetrahydro-4,7-ethanethieno

[2,3-b]pyridine-3-carboxamide.

N,N-dimethyl-2-amino-4,5,6,7-tetrahydro-4,7-

ethanethieno[2,3-b]pyridine-3-carboxamide.

50 N-methyl-N-butyl-2-amino-4,5,6,7-tetrahydro-4,7-

ethanethieno[2,3-b]pyridine-3-carboxamide.

2-amino-4,5,6,7-tetrahydro-4,7-ethanethieno[2,3-b]

pyridine-3-thiocarboxamide.

N-methyl-2-amino-4,5,6,7-tetrahydro-4,7-ethanethieno

[2,3-b]pyridine-3-thiocarboxamide.

55 N-methyl-N-propyl-2-amino-4,5,6,7-tetrahydro-4,7-

ethanethieno[2,3-b]pyridine-3-thiocarboxamide.

The compounds of this invention are prepared by treating 60 3-quinuclidinone with a mixture of an appropriate nitrile, sulfur and morpholine.

The following examples are presented to further illustrate the method of preparing the compounds of this invention.

Example 1.—2-amino-4,5,6,7-tetrahydro-4,7-ethanethieno[2,3-b]pyridine-3-carbonitrile

A solution of 0.1 mole of malonitrile in 20 ml. of ethanol is added to a stirred mixture of 0.1 mole of 3-quinuclidinone, 0.11 mole of sulfur and 3.0 ml. of morpholine in 80 ml. of ethanol. The reaction mixture is then warmed to 50° C. and held at that temperature for 4 hours under an atmosphere of nitrogen. After cooling to ice

bath temperature, the precipitated solids are removed by filtration and recrystallized from aqueous dimethylformamide to give 2-amino-4,5,6,7-tetrahydro-4,7-ethanothieno[2,3-b]pyridine-3-carbonitrile, M.P. 200-201° C.

The hydrochloride salt of this compound is prepared by passing dry hydrogen chloride gas into an ethanolic solution of the base. The salt is recrystallized from ethanol/water to give 2-amino-4,5,6,7-tetrahydro-4,7-ethanothieno[2,3-b]pyridine-3-carbonitrile hydrochloride, M.P. 273-274° C.

Example 2.—Ethyl 2-amino-4,5,6,7-tetrahydro-4,7-ethanothieno[2,3-b]pyridine-3-carboxylate

A solution of 0.1 mole of ethyl cyanoacetate in 20 ml. of ethanol is added to a stirred mixture of 0.1 mole of 3-quinuclidinone, 0.11 mole of sulfur and 3.0 ml. of morpholine in a solution of 80 ml. of ethanol. The reaction mixture is then warmed to 40° C. and stirred overnight at this temperature. After cooling to room temperature, the mixture is filtered and the filtrate is poured into 400 ml. of water containing 4 ml. of glacial acetic acid to give a semisolid mass. The aqueous phase is decanted off and the semisolid material is washed four times with 200 ml. of water containing 2 ml. of glacial acetic acid. The residue is recrystallized from acetonitrile to give ethyl 2-amino-4,5,6,7-tetrahydro-4,7-ethanothieno[2,3-b]pyridine-3-carboxylate, M.P. 148-149° C.

The hydrochloride salt of this compound is prepared by passing dry hydrogen chloride gas into an ethanolic solution of the base. The salt is recrystallized from ethanol/water to give ethyl 2-amino-4,5,6,7-tetrahydro-4,7-ethanothieno[2,3-b]pyridine-3-carboxylate hydrochloride, M.P. 259-260° C.

Examples 3-5

The procedure of Example 2 is repeated, substituting the indicated cyanoacetic ester for the ethyl cyanoacetate of Example 2 to obtain the indicated product.

Ex.	Ester	Product
3.....	Methyl cyanoacetate.....	Methyl 2-amino-4,5,6,7-tetrahydro-4,7-ethanothieno[2,3-b]pyridine-3-carboxylate.
4.....	Isopropyl cyanoacetate...	Isopropyl 2-amino-4,5,6,7-tetrahydro-4,7-ethanothieno[2,3-b]pyridine-3-carboxylate.
5.....	n-Hexyl cyanoacetate...	n-Hexyl 2-amino-4,5,6,7-tetrahydro-4,7-ethanothieno[2,3-b]pyridine-3-carboxylate.

Example 6.—2-amino-4,5,6,7-tetrahydro-4,7-ethanothieno[2,3-b]pyridine-3-carboxylic acid

A solution of 0.1 mole of ethyl 2-amino-4,5,6,7-tetrahydro-4,7-ethanothieno[2,3-b]pyridine-3-carboxylate in 100 ml. of acetic anhydride is warmed to 50° C. for 2 hours. The reaction mixture is then cooled to room temperature and poured on a mixture of 200 gm. of ice and 200 ml. of water and stirred for one hour. The mixture is neutralized by adding concentrated ammonium hydroxide while keeping the temperature below 20° C. The precipitated solid is recrystallized from acetonitrile to give ethyl 2-acetamido-4,5,6,7-tetrahydro-4,7-ethanothieno[2,3-b]pyridine-3-carboxylate, M.P. 194-195° C.

A solution of 0.1 mole of this ester and 12.0 gm. of sodium hydroxide in 175 ml. of water and 125 ml. of dioxane is refluxed for 1½ hours. The reaction mixture is concentrated in vacuo to about one half of its original volume and any insoluble material is removed by filtration. The filtrate is stirred and cooled to 10° C. and glacial acetic acid is added slowly until the solution reaches pH 7. The precipitate which forms is filtered off and dried in a desiccator over calcium chloride to yield 2-amino-4,5,6,7-tetrahydro-4,7-ethanothieno[2,3-b]pyridine-3-carboxylic acid.

Example 7.—2-amino-4,5,6,7-tetrahydro-4,7-ethanothieno[2,3-b]pyridine-3-carboxamide

A solution of 0.1 mole of 2-cyanoacetamide in 50 ml. of dimethylformamide is added to a stirred mixture of 0.1 mole of 3-quinuclidinone, 0.11 mole of sulfur and 3.0 ml. of morpholine in 50 ml. of dimethylformamide. The reaction mixture is warmed to 50° C. and held at that temperature for 4 hours under an atmosphere of nitrogen. After cooling to room temperature, the mixture is poured into 500 ml. of water containing 5 ml. of glacial acetic acid to give a precipitate which is collected by filtration. Crystallization of this solid from acetonitrile gives 2-amino-4,5,6,7-tetrahydro-4,7-ethanothieno[2,3-b]pyridine-3-carboxamide, M.P. 195-197° C.

Examples 8-10

The procedure of Example 7 is repeated, substituting the indicated "cyanoacetamide" for the 2-cyanoacetamide of Example 7 to obtain the indicated product.

Ex.	Cyanoacetamide	Product
8.....	N,N-dimethyl-2-cyanoacetamide.	N,N-dimethyl-2-amino-4,5,6,7-tetrahydro-4,7-ethanothieno[2,3-b]pyridine-3-carboxamide.
9.....	N-propyl-2-cyanoacetamide.	N-propyl-2-amino-4,5,6,7-tetrahydro-4,7-ethanothieno[2,3-b]pyridine-3-carboxamide.
10....	N-ethyl-N-methyl-2-cyanoacetamide.	N-ethyl-N-methyl-2-amino-4,5,6,7-tetrahydro-4,7-ethanothieno[2,3-b]pyridine-3-carboxamide.

Example 11.—2-amino-4,5,6,7-tetrahydro-4,7-ethanothieno[2,3-b]pyridine-3-thiocarboxamide

A solution of 0.1 mole of 2-amino-4,5,6,7-tetrahydro-4,7-ethanothieno[2,3-b]pyridine-3-carbonitrile in 30 ml. of pyridine and 0.1 mole of triethylamine is treated with dry hydrogen sulfide by passing the gas through the solution in a steady stream for 2-3 hours. The mixture is then poured into water and the precipitate which forms is filtered off and dried to give 2-amino-4,5,6,7-tetrahydro-4,7-ethanothieno[2,3-b]pyridine-3-thiocarboxamide.

Example 12.—N-propyl-2-amino-4,5,6,7-tetrahydro-4,7-ethanothieno[2,3-b]pyridine-3-thiocarboxamide

A mixture of 0.1 mole of N-propyl-2-amino-4,5,6,7-tetrahydro-4,7-ethanothieno[2,3-b]pyridine-3-carboxamide and 20.0 gm. of phosphorus pentasulfide in 250 ml. of xylene is stirred vigorously and refluxed for 2 hours. The mixture is then cooled in an ice-bath and an excess of 10% sodium hydroxide solution is added dropwise.

The aqueous layer is separated and neutralized by the addition of glacial acetic acid. The precipitate which forms is filtered off and dried to give N-propyl-2-amino-4,5,6,7-tetrahydro-4,7-ethanothieno[2,3-b]pyridine-3-thiocarboxamide.

Example 13.—N,N-dimethyl-2-amino-4,5,6,7-tetrahydro-4,7-ethanothieno[2,3-b]pyridine-3-thiocarboxamide

A mixture of 0.1 mole of N,N-dimethyl-2-amino-4,5,6,7-tetrahydro-4,7-ethanothieno[2,3-b]pyridine-3-carboxamide and 20.0 gm. of phosphorus pentasulfide in 250 ml. of xylene is stirred vigorously and refluxed for 2 hours. The mixture is then cooled in an ice-bath and an excess of 10% sodium hydroxide solution is added dropwise. The mixture is stirred for an additional 15 minutes and then filtered to give a residue of N,N-dimethyl-2-amino-4,5,6,7-tetrahydro-4,7-ethanothieno[2,3-b]pyridine-3-thiocarboxamide.

The active ingredient of this invention can be employed in useful compositions according to the present invention in such dosage forms as tablets, capsules, powder, packets, or liquid solutions, suspensions, or elixirs, for oral administration or liquid for parenteral use, and in certain cases, suspensions for parenteral use (except intravenous). The compounds may also be applied topically in solution, lotion or ointment form. In the pharmaceutical compositions of this invention the active ingredient will ordinarily

always be present in an amount of at least 0.5% by weight based on the total weight of the composition and not more than 99% by weight.

Besides the active ingredient of this invention, the antiviral composition will contain a solid or liquid non-toxic pharmaceutical carrier for the active ingredient.

In one embodiment of a pharmaceutical composition of this invention, the solid carrier is a capsule which can be of the ordinary gelatin type. In the capsule will be from about 30-99% by weight of a compound of Formula 1 and 70-1% of a carrier. In another embodiment, the active ingredient is tableted with or without adjuvants. In yet another embodiment, the active ingredient is put into powder packets and employed. In these capsules, tablets and powders the active ingredient will generally constitute from about 5% to about 99% and preferably from 25% to 90% by weight. These dosage forms preferably contain from about 5 to about 500 milligrams of active ingredient, with from about 25 to about 250 most preferred.

The pharmaceutical carrier can, as previously indicated, be a sterile liquid such as water and oils, including those of petroleum, animal, vegetable or synthetic origin, for example peanut oil, soybean oil, mineral oil, sesame oil, and the like. In general, water saline, aqueous dextrose (glucose) and related sugar solutions and glycols such as propylene glycol or polyethylene glycols are preferred liquid carriers, particularly for injectable solutions. Sterile injectable solutions such as saline will ordinarily contain from about 0.5% to 25% and preferably about 1 to 10% by weight of the active ingredient.

As mentioned above, oral administration can be in a suitable suspension or syrup, in which the active ingredient ordinarily will constitute from about 0.5 to 10% and preferably about 2 to 5%, by weight. The pharmaceutical carrier in such composition can be a watery vehicle such as an aromatic water, a syrup or a pharmaceutical mucilage.

Suitable pharmaceutical carriers are described in "Remington's Pharmaceutical Sciences" by E. W. Martin, a well-known reference text in this field.

In addition to the exemplary illustrations above, the following examples further explain the present invention.

Example 14

A large number of unit capsules are prepared by filling standard two-piece hard gelatin capsules weighing about 50 milligrams each with 250 milligrams of powdered 2 - amino - 4,5,6,7 - tetrahydro - 4,7 - ethanothieno-[2,3-b]pyridine - 3 - carbonitrile, hydrochloride, 110 milligrams of lactose, 1 milligram of "Cab-o-Sil," 8 milligrams of magnesium stearate and 32 milligrams of talc.

Example 15

Soft gelatin capsules can be prepared by dissolving or suspending powdered 2-amino - 4,5,6,7 - tetrahydro-4,7 - ethanothieno[2,3-b]pyridine - 3 - carbonitrile in soybean oil.

Example 16

A large number of tablets are prepared by conventional procedures so that the dosage unit is 50 milligrams of active ingredient, 5 milligrams of gelatin, 1.5 milligrams of magnesium stearate and 100 milligrams of lactose. Slow release pills or tablets can also be prepared by applying appropriate coatings. A sugar coating may be applied to increase palatability.

Example 17

A parenteral composition suitable for administration by injection is prepared by stirring 5% by weight of ethyl 2 - amino - 4,5,6,7 - tetrahydro - 4,7 - ethanothieno-

[2,3-b]pyridine - 3 - carboxylate hydrochloride in sodium chloride injection, and filtering the solution through a sterilizing filter.

Example 18

5 A composition for topical application is prepared by triturating 10% by weight of the active ingredient in hydrophilic ointment, U.S.P.

10 A large variety of compositions according to this invention can thus readily be made by substituting other compounds of this invention, and including specifically but not limited to compounds of this invention that have specifically been named hereinbefore. The compounds will be used in the amounts indicated in accordance with procedures well known and described in the Martin text mentioned above.

15 It will be understood that a "warm-blooded animal" is a member of the animal kingdom possessed of a homeostatic mechanism and includes mammals and birds.

20 The antiviral effectiveness of the compounds of this invention can be demonstrated against Herpes virus when a medium containing at least 10 mcg./ml. of 2-amino-4,5,6,7 - tetrahydro - 4,7 - ethanothieno[2,3-b]pyridine-3-carbonitrile, hydrochloride is applied to rabbit kidney cells which have been infected with 200 plaque forming units of *Herpes simplex/H4*/virus with the result that complete inhibition of the cytopathic effect of the virus is noted.

25 2-amino - 4,5,6,7 - tetrahydro - 4,7 - ethanothieno[2,3-b]pyridine - 3 - carbonitrile hydrochloride when applied at a concentration of ten mcg./ml. is also effective in preventing damage to mouse embryo cells which have been infected with 300 plaque forming units of *Herpes simplex/2/ALA/SM* virus.

30 35 A local application of 20 mcg. of 2-amino - 4,5,6,7 - tetrahydro - 4,7 - ethanothieno[2,3-b]pyridine - 3 - carboxylic acid, ethyl ester to a cell monolayer of rabbit kidney cells infected with *Herpes simplex/H4* virus effectively inhibits the cytopathic effect of the virus on said cells.

40 45 A local application of 80 mcg. of 2 - amino - 4,5,6,7 - tetrahydro - 4,7 - ethanothieno[2,3-b]pyridine - 3 - carboxamide to a cell monolayer of rabbit kidney cells infected with *Herpes simplex/H4* virus effectively inhibits the cytopathic effect of the virus on said cells.

50 55 The effectiveness of 2 - amino - 4,5,6,7 - tetrahydro-4,7 - ethanothieno[2,3-b]pyridine - 3 - carbonitrile, hydrochloride in combating *Herpes simplex/H4* infections in guinea pigs can be demonstrated as follows:

Guinea pigs are shaved and infected intradermally on 18 sites, 9 sites per side, with *Herpes simplex/H4* virus. The test compound, 2 - amino - 4,5,6,7 - tetrahydro-4,7 - ethanothieno[2,3-b]pyridine - 3 - carbonitrile, dissolved in a vehicle consisting of 90% dimethylsulfoxide and 10% water is administered topically at 24, 48, 72 and 96 hours after infection. Seven days after infection the guinea pigs treated with the above mixture are compared to a control group of guinea pigs infected with said virus but which are treated with the vehicle only. Control animals show 86% positive lesions whereas animals treated with 0.375 mg./site of 2 - amino - 4,5,6,7 - tetrahydro - 4,7 - ethanothieno[2,3-b]pyridine - 3 - carbonitrile hydrochloride show only 38% positive lesions.

60 65 The antiviral effectiveness of the compounds of this invention can be demonstrated against adenovirus when a medium containing 80 mcg. of 2 - amino - 4,5,6,7 - tetrahydro - 4,7 - ethanothieno[2,3-b]pyridine - 3 - carbonitrile is locally applied to an agar medium containing HEp-2 cell monolayers which are infected with Adeno-virus 2 and incubated at 37° C. for seven days. After the incubation period, it is found that the tissue surrounding the medicated area is normal while other areas of the infected tissue is heavily damaged. The result demonstrates that the test compound effectively inhibits the growth of adenovirus-2.

I claim:

1. A compound of the formula:

where R₁ iswhere

R₂ is hydrogen or alkyl of one through six carbon atoms; 15
X is oxygen or sulfur;R₃ is hydrogen or alkyl of one through four carbon
atoms;R₄ is hydrogen or alkyl of one through four carbon
atoms; andthe pharmaceutically acceptable non-toxic salts of said
compounds.

2. The compound of claim 1 which is 2-amino-4,5,6,7-

tetrahydro-4,7-ethanothieno[2,3-b]pyridine - 3 - carbo-
nitrile.3. A pharmaceutically acceptable non-toxic salt of the
compound of claim 2.4. The compound of claim 1 which is 2-amino-4,5,6,7-
tetrahydro - 4,7 - ethanothieno[2,3-b]pyridine-3-carbox-
ylic acid ethyl ester.5. A pharmaceutically acceptable non-toxic salt of the
compound of claim 4.10 6. The compound of claim 1 which is 2-amino-4,5,6,7-
tetrahydro-4,7-ethanothieno[2,3-b]pyridine - 3 - carbox-
amide.7. A pharmaceutically acceptable non-toxic salt of the
compound of claim 6.
